UNITED STATES PATENT OFFICE.

DAVID O. PAIGE, OF DETROIT, MICHIGAN.

FLANGING-MACHINE.

SPECIFICATION forming part of Letters Patent No. 425,453, dated April 15, 1890.

Application filed November 2, 1889. Serial No. 329,019. (No model.)

To all whom it may concern:

Be it known that I, DAVID O. PAIGE, a citizen of the United States, residing at Detroit, county of Wayne, State of Michigan, have invented a certain new and useful improvement in Flanging-Machines; and I declare the following to be a full, clear, and exact description of the invention, such as will enable others skilled in the art to which it pertains to make and use the same, reference being had to the accompanying drawings, which form a part of this specification.

In the drawings, Figure 1 is a front elevation of a machine embodying my invention. Fig. 2 is a side elevation of the same. Fig. 3 is a plan view. Fig. 4 is a horizontal section. Fig. 5 illustrates a variation in which the anvil is made in removable sections.

It is the purpose of my invention to produce a machine for turning flanges on large cylindrical rings, more particularly rings that are employed in the construction of large tanks used in the manufacture of beer and other like purposes. Great difficulty has heretofore been experienced in the formation of such flanges on heavy rings of this character, and they have generally been heated at the edge a little at a time and turned with hammers while the metal was hot. So, also, it has been done by crimping the edge of the metal between two rollers and gradually turning the edge outwardly. In the former case, however, the process was slow and the work was rough at the best, and in the latter it was impossible to make a flat flange, and in both it was difficult to make a joint with any other similar flange or surface.

In carrying out my invention, A represents the head of a chuck secured to a shaft A' and journaled at A²A³ in a suitable bed or frame B.

C C' represent a case or shell, within which the cylindrical ring is fastened when it is to have the flanges turned upon it. The shell shown has one of its sections made permanently with, or rather fastened permanently to, the face of the disk—as, for instance, the section C—while the section C' or other sections are adapted to be shifted out from the center temporarily, in order to facilitate the introduction or removal of one of the metallic rings. This is especially necessary after a flange has been turned upon one end of the

ring and the ring has to be reversed in order to turn the flange at the opposite end.

c represents blocks located upon the interior of the metallic casing on the face of the chuck. They are to facilitate the centering of the ring upon the chuck. Set-screws c' render this operation still more accurate. One of the rings is shown in position ready to have the flange turned upon it. It is illustrated by dotted lines in Fig. 4.

c² represents recesses in blocks which are cast upon the chuck or upon the interior of the metallic casings. These recesses are designed to receive and form a bearing for the turned flange when the ring is reversed in order to have a flange turned upon its other end. They serve to hold the metallic ring in proper position so that a sufficient amount of the end of the ring will project out from the casing to form the other flange.

I do not limit myself to a construction in which the case or shell C C' is made in sections, made removable or adapted to shift outwardly to admit a ring, for this case may, if desired, be formed integral with or be attached permanently to the chuck and have a large enough interior diameter to admit the ring after a flange has been turned upon one end. In this event blocks c c² may be provided of suitable nature to properly locate and retain the ring within the case or shell.

When the shell is made as last explained, its outer end may be provided with removable or adjustable segments C², which constitute the anvil over and upon which the flange is turned and formed, and pins C³ may or may not be passed through from the exterior to hold the flanged end in place. Such a variation is shown in Fig. 5.

D represents an upright crane. It is adapted to be revolved horizontally about its axis.

D' represents a plane or table in the form of a segment with cogged gearing at its edge 95 engaging and operated by the pinion D². This pinion D² is operated by means of bevel-gearing D³, actuated by a hand-wheel D⁴ or other suitable means. The crane and table are adapted to support the shaft E, which has the flanging-roll E' upon its end. E² is an adjusting-screw at the end of this shaft, whereby it may be set out farther in the direction of its length, as shown by the dotted lines in

Fig. 4, in order to adjust it to its proper position with respect to the flange which is to be turned. E³ is another adjusting-screw, whereby this flanging-roll may be adjusted in a direction at right angles to its own shaft, and so set in nearer to or farther from the flange that is being turned.

F is an abutment-roll located back of the face of the chuck, in order to receive and sustain the thrust upon the chuck which is given by the turning-roll.

G represents the gearing back of the chuck A.

G' is a working pinion which meshes with this gearing, and is in turn driven by the cog-wheels or other suitable gearing G², which are connected with the driving-belts. I would, however, have it understood that any suitable gearing may be employed instead of the particular gearing shown.

H is a bridge or support between the main frame and the upright crane. The crane may be adjusted to any particular position by reason of the fact that it is sustained by bolts a, engaged in intersecting grooves b, formed in the base-plate. It is now apparent that if it is desired to operate upon a longer cylindrical ring it is only necessary to lengthen out the shell C C'—that is to say, to employ a new shell of suitable size—and adjust the crane on the base-plate and put in a corresponding bridge H. This shell or case C C' at its outer edge is so shaped as to form an anvil, upon which the flanging-roll turns the edge of the metal in forming the flange.

To operate this device, the cylindrical ring upon which the flanges are to be turned is introduced and properly adjusted into the cylindrical case C C', sufficient projecting beyond the end of the cylindrical case to form the flange. The flanging-roll is then properly adjusted in position and the chuck is set in motion. The operator then, with the flanging-wheel, gradually turns the flange as the cylindrical ring is revolved. It is apparent that he soon turns it down upon the outer ends of the cylindrical case as an anvil, and that the flange thus produced has a square angle with the remaining portion of the cylindrical ring. It is also made perfectly flat and true.

Upon this device I have been able to turn with ease the flanges upon rings seven to eight feet in diameter and upon metal of a quarter of an inch or more in thickness. The metal is manipulated cold and requires no heating for this purpose. As the flange is being turned, it is apparent that the flanging-roll may be adjusted in or out or nearer to or farther from the ring, to conform at all times to the requirements of the work.

In using the term "metallic shell or case" in the claims I would be understood as meaning either the form in which the shell or case is itself made in segments adapted to shift to or from the center of the chuck or a shell permanently secured and with adjustable an-

vil portions at its end. Of course both the segments of its anvil end may be made independently adjustable, if desired.

What I claim is—

1. In a machine for turning flanges upon large cylindrical rings, the combination of a chuck, a metallic case or shell adapted to inclose the ring and provided at its outer end with an anvil-surface upon which the flange is turned, an adjustable vertical crane, an adjustable flanging-roll carried by said crane, and an abutment-roller located back of the chuck to receive the thrust of the flanging-roll, substantially as described. 70

2. In a machine for turning flanges upon large cylindrical rings, the combination of a chuck, a case or shell adapted to inclose the ring and provided at its outer end with an anvil-surface upon which the flange is turned, the blocks c, for centering the inner end of the ring, the crane provided with a flanging-roll, and the abutment-roll located back of the chuck, substantially as described. 75

3. In a machine for turning flanges upon large cylindrical rings, the combination of a chuck, a case or shell adapted to inclose the ring and provided on its outer end with an anvil-surface upon which the flange is turned, channeled blocks for centering the inner end 80 of the ring and for receiving the turned flange on one end of the ring, a crane, a flanging-roll carried by said crane, and means for adjusting the flanging-roll, substantially as described. 90

4. In a machine for turning flanges upon large cylindrical rings, the combination of the chuck, the cylindrical shell or case adapted to receive the ring, adjustable sections forming part of the outer end of said casing and removable for admitting or removing the cylindrical ring, and a crane carrying a flanging-roll, substantially as described. 105

5. In a machine for turning flanges upon large cylindrical rings, the combination, with the chuck and the cylindrical case C C', of the blocks provided with channels c², for receiving the turned flange at one end of the cylindrical ring and holding the ring in its proper position with respect to the chuck as 110 the flange is being turned upon the other end of the cylindrical ring, substantially as described. 115

6. In a machine for turning flanges upon large cylindrical rings, the combination, with a chuck, of a cylindrical case for holding the ring, a vertical crane bearing the flanging-roll and means for operating the said crane, and an abutment-roll located back of the face of the chuck for receiving the thrust of 120 the flanging-roll, substantially as described. 125

In testimony whereof I sign this specification in the presence of two witnesses.

DAVID O. PAIGE.
